TYPEWRITING MACHINE

Remo Walter Petrini, Hartford, Conn., assignor to
 Royal Typewriter Company, Inc., New York,
 N. Y., a corporation of New York

Application December 6, 1935, Serial No. 53,236

9 Claims. (Cl. 197—70)

This invention relates to new and useful improvements in typewriting machines generally, although more particularly to a column stop unit and to the method of assembling the same.

5 The Myers and Handley Patent 1,926,165, Sept. 12, 1933, discloses a column stop unit wherein, should one of the stops become broken due to impact of said stop against the stop lever, it is necessary to first remove one end plate and then 10 remove the stops until the broken stop is reached, before said broken stop can be removed and a new one substituted.

The principal object of the present invention is to provide a column stop unit wherein all of the 15 stops are mounted for individual removal whereby should any stop become broken it can be readily removed and a new stop substituted.

Another important object of the invention is to provide removable means for preventing the 20 accidental removal of any of said column stops.

A further object of the invention is to provide a novel method of assembling the unit.

In the drawing:

Figure 1 is a top plan view of a margin stop 25 unit constructed in accordance with my invention,

Figure 2 is a view partly in front elevation and partly in section of said unit,

Figure 3 is a cross-sectional view taken on the 30 line 3—3 of Figure 2,

Figure 4 is a cross-sectional view showing the first step in assembling one of the margin stops on the supporting frame,

Figure 5 is an enlarged sectional view similar 35 to Figure 3, but showing the limiting stop removed,

Figure 6 is an enlarged rear elevation of the 40 unit showing particularly one of the intermediate tie plates for the frame rack bars, and also the means of attaching one of the limiting or stop plates to the upper rack bar,

Figure 7 is a cross-sectional view taken on the line 7—7 of Figure 6,

Figure 8 is a view similar to Figure 6 but showing the column stop partially removed,

Figure 9 is a perspective view showing a portion of the upper rack bar,

Figure 10 is a perspective view showing one end of one of the limiting stop plates, and

50 Figure 11 is a cross-sectional view showing the initial step in assembling the rack bars and intermediate tie plates.

Referring to the accompanying drawing, A designates a column stop frame which is removably mounted on the end plates 5, 5 of a type-

writer carriage. This frame includes a pair of spaced upper and lower rack bars 6, 7 which are rigidly connected together at their ends by end plates 8, 8, and screws 9 which pass through the plates into threaded openings in the ends of the bars. Rigidly connected to each plate 8 is an outwardly projecting threaded stud 10 which is clamped to the adjacent end plate 5 of the carriage by nuts 11. The frame A is held against turning by brackets which, as shown in Figures 1, 2, and 3, are secured to the end plates 5 of the carriage and to the frame. The rack bars 6, 7 are rectangular in cross-section except that the top surface 12 of the upper bar is transversely rounded throughout its length. The lower face of the upper bar and the upper face of the lower bar are respectively formed with grooves 13 and 14 arranged in opposed pairs and spaced apart distances corresponding to letter space intervals. These bars are held against spreading actions between their ends, by intermediate tie plates 15. Each tie plate is formed with spaced openings 16, 17 to receive the rack bars 6, 7 respectively, each opening being of a larger cross-sectional area than the associated rack bar. The upper surface 18 of the upper rack bar 6 and the lower surface 19 of the lower rack bar 7, are formed with transverse seats 19, 20 for receiving the upper and lower cross bars 21, 22 of the tie plates to thereby interlock said tie plates with the rack bars.

Supported on the frame A is a series of column stops B, there being one of these stops for each pair of upper and lower grooves 13, 14, and therefore these stops are located at letter space intervals. Each stop is of H-shaped construction and includes spaced and upwardly converging front and rear arms 23, 24, spaced and downwardly extending short front and rear legs 25, 26, and a cross bar or connecting portion 27. Each stop B is positioned on the frame A so that the arms 23, 24 are disposed on opposite sides of the upper rack bar 6 and the legs 25, 26 are disposed on opposite sides of the lower rack bar 7, the cross bar 27 extending between the bars 6, 7 and into the upper and lower transverse grooves 13, 14 thereof. The upper ends of the arms 23, 24 are rounded and the distance between these ends is a trifle greater than the width of the upper rack bar 6 so as to permit the stop to swing from an inactive forward position to an active rearward position or vice versa, the rounded ends constituting pivots or fulcra for the stop. The legs 25, 26 are spaced apart a distance considerably greater than the width of

the lower rack bar 1 so as to permit the stop being swung from one extreme position to the other, the legs cooperating with said rack bar to limit the swinging movement of the stop. The 5 lower edge of the bridge portion 27 adjacent the rear leg 26 is angled and is provided with a flat 28 which rests on the bottom wall 14^a of the groove 14 when the stop B is in its inactive or inoperative position. The lower edge of the 10 bridge portion 27 between the front leg 25 and the flat 28 is formed with a recess 29 to form a clearance and thereby permit the free rearward swinging of the stop B. The stop is retained frictionally in each of its extreme positions, and 15 to this end the stop is provided with a spring 30 which is in the form of a spring wire bent between its ends to form upper and lower spring arms 31, 32 respectively, the bend of the spring engaging a headed stud 33 which is attached to 20 the right hand face of the stop. The arms 31, 32 extend forwardly between the upper and lower rack bars 6, 7 and the free end of the lower arm 32 is rebent as at 34 to engage the front edge of the stop directly above and rest upon 25 a shoulder 35 formed on said stop. The free end of the upper arm 31 is curved upwardly and downwardly to form a cam which has sliding engagement with the lower face of the upper rack bar 6 when the stop is in its active position, and 30 with the lower front corner of the upper rack bar when the stop is in its inactive position. Thus, the stop B is capable of being rocked rearwardly to an active position or forwardly to an inactive position, and yieldable means are provided for 35 automatically and frictionally retaining the stop in either of its extreme positions.

It will be noted that the distance between the top wall 13^a of each groove 13 and the upper edge of the bridge 27 of the associated stop, is 40 considerably greater than the length of the legs 25, 26 of the stop. Consequently, each stop can be readily removed from the frame A by first raising the stop bodily against the tension of the associated spring 33, and then by swinging the stop either forwardly or rearwardly to disengage the same from the frame. In assembling 45 the unit, each stop B is first positioned as in Figure 4 with the arms 23, 24 embracing the upper rack bar 6, and with pressure being exerted on the stop against the tension of the spring 30. The stop is then swung rearwardly to a position between the rack bars 6, 7, and then released, as shown in Figure 3.

In order to prevent accidental removal of the 55 column stop B, a displaceable limiting stop C is attached by screws 37 to the top surface 12 of the upper rack bar 6. This limiting stop C is in the nature of an elongated plate which is transversely curved, and the longitudinal edges 60 of the plate are disposed in the path of the upward movement of the column stops B, and function to prevent said stops being raised sufficiently to allow the stops to be removed. When it is desired to replace any broken column stop, 65 the limiting stop C is first displaced, the broken column stop is then removed in the manner above described, a new column stop is then applied, and the limiting stop C is then repositioned.

The method employed in assembling the unit 70 is as follows: The upper and lower rack bars are first projected through the openings of the tie plates 15; the rack bars are then spread apart and the tie plates are then engaged in the transverse seats 19, 20 of the bars; the end 75 plates 8, 8 are then connected to the bars while

the bars are held in their spread relation; the column stops B, are then applied to the frame, and finally the limiting stop C is attached to the upper rack bar 6.

I claim:

1. In a column stop unit for typewriting and like machines, the combination of a frame including a pair of rack bars arranged in a fixed and parallel relation and having their inner faces provided with opposed pairs of transverse grooves 10 arranged at spaced intervals, and a plurality of column stops individually mounted for removal in the respective opposed pairs of grooves of the rack bars, said stops being transversely swingable from an inactive to an active position and vice 15 versa.

2. In a column stop unit for typewriting and like machines, the combination of a frame including a pair of rack bars arranged in a fixed and parallel relation and having their inner faces 20 provided with opposed pairs of transverse grooves arranged at spaced intervals, a plurality of column stops individually mounted for removal in the respective opposed pairs of grooves of the rack bars, and yieldable means cooperating 25 with each stop and one bar for yieldably retaining the stop against the other bar, said stop being bodily movable towards the first bar and transversely swingable to a disengaged position with respect to the frame.

3. In a column stop unit for typewriting and like machines, the combination of a frame including a pair of rack bars arranged in a fixed and parallel relation and having their inner faces 35 provided with opposed pairs of transverse grooves arranged at spaced intervals, a plurality of column stops individually mounted for removal in the respective opposed pairs of grooves of the rack bars, said stops being transversely swingable from an inactive to an active position and vice 40 versa, and yieldable means cooperating with each stop and one bar for yieldably retaining the stop against the other bar, said stop being bodily movable towards the first bar and transversely swingable to a disengaged position with respect 45 to the frame.

4. In a column stop unit for typewriting and like machines, the combination of a frame including a pair of rack bars arranged in a fixed and parallel relation and having their inner faces 50 provided with opposed pairs of transverse grooves arranged at spaced intervals, and a plurality of column stops individually mounted for removal in the respective opposed pairs of grooves of the rack bars, each stop comprising spaced arms 55 embracing the upper rack bar and having pivotal engagement therewith, spaced legs embracing the lower rack bar and cooperating with the bar to limit the swinging movements of the stop, and a bridge connecting the arms and legs and disposed between the bars and slidably engaging in the upper and lower grooves of the bars, and a spring mounted on each stop for cooperation with the upper bar for frictionally retaining the stop against the lower bar in either extreme position of movement of the stop, the distance between the upper edge of the bridge and the top wall of the associated upper groove being considerably greater than the length of the legs whereby said stop can be raised bodily against 65 the tension of the spring and then swung transversely of the frame to a disengaged position with respect to the latter.

5. In a column stop unit for typewriting and like machines, the combination of a frame in- 75

- cluding a pair of rack bars arranged in a fixed and parallel relation and having their inner faces provided with opposed pairs of transverse grooves arranged at spaced intervals, a plurality of column stops individually mounted for removal in the respective opposed pairs of grooves of the rack bars, said stops being transversely movable from an inactive position to an active position and vice versa, and a displaceable limiting stop mounted on one of the bars for cooperation with a plurality of column stops to normally prevent the latter from becoming accidentally removed. 5
6. In a column stop unit for typewriting and like machines, the combination of a frame including a pair of rack bars arranged in a fixed and parallel relation and having their inner faces provided with opposed pairs of transverse grooves arranged at spaced intervals, a plurality of column stops individually mounted for removal in the respective opposed pairs of grooves of the rack bars, each stop comprising spaced arms embracing the upper rack bar and having pivotal engagement therewith, spaced legs embracing the lower rack bar and cooperating with the bar to limit the swinging movements of the stop, and a bridge connecting the arms and legs and disposed between the bars and slidably engaging in the upper and lower grooves of the bars, a spring mounted on each stop for cooperation with the upper bar for frictionally retaining the stop against the lower bar in either extreme position of movement of the stop, the distance between the upper edge of the bridge and the top wall of the associated upper groove being considerably greater than the length of the legs whereby said stop can be raised bodily against the tension of the spring and then swung transversely of the frame to a disengaged position with respect to the latter, and a displaceable limiting stop mounted on the upper rack bar for cooperation with a plurality of column stops to normally prevent the latter from becoming accidentally removed. 10
7. In a column stop unit for typewriting and like machines, the combination of a frame including a pair of rack bars arranged in a fixed and parallel relation and having their inner faces provided with opposed pairs of transverse grooves arranged at spaced intervals, a plurality of column stops individually mounted for removal in the respective opposed pairs of grooves of the rack bars, yieldable means cooperating with each stop and one bar for yieldably retaining the stop against the other bar, said stop being bodily movable towards the first bar and transversely swingable to a disengaged position with respect to the frame, and a displaceable limiting stop mounted on one of the bars for cooperation with a plurality of column stops to normally prevent the latter from becoming accidentally removed. 15
8. In a column stop unit for typewriting and like machines, the combination of a frame including a pair of rack bars arranged in a fixed and parallel relation and having their inner faces provided with opposed pairs of transverse grooves arranged at spaced intervals, and a plurality of column stops individually mounted for removal in the respective opposed pairs of grooves of the rack bars, each stop comprising spaced arms embracing the upper rack bar and having pivotal engagement therewith, spaced legs embracing the lower rack bar and cooperating with the bar to limit the swinging movements of the stop, and a bridge connecting the arms and legs and disposed between the bars and slidably engaging in the upper and lower grooves of the bars, a spring mounted on each stop for cooperation with the upper bar for frictionally retaining the stop against the lower bar in either extreme position of movement of the stop, the distance between the upper edge of the bridge and the top wall of the associated upper groove being considerably greater than the length of the legs whereby said stop can be raised bodily against the tension of the spring and then swung transversely of the frame to a disengaged position with respect to the latter, and a displaceable limiting stop mounted on the upper rack bar for cooperation with a plurality of column stops to normally prevent the latter from becoming accidentally removed, said limiting stop comprising a plate extending longitudinally of the frame and attached to the upper surface of the upper rack bar, the longitudinal edges of the plate cooperating with the upper ends of the arms of the column stop to limit the upward movement of the latter. 20
9. In a column stop unit for typewriting and like machines, the combination of a frame including a pair of rack bars arranged in spaced parallel relation and with the transverse grooves thereof disposed opposite each other, end plates secured to the ends of the bars, column stops mounted in the grooves of the bars and movable transversely of the bars from an inactive to an active position and vice versa, said bars having transverse seats formed in their outer faces, and a tie plate connecting the bars and having interlocking engagement in said seats. 25
7. In a column stop unit for typewriting and like machines, the combination of a frame including a pair of rack bars arranged in a fixed and parallel relation and having their inner faces provided with opposed pairs of transverse grooves arranged at spaced intervals, a plurality of column stops individually mounted for removal in the respective opposed pairs of grooves of the rack bars, each stop comprising spaced arms embracing the upper rack bar and having pivotal engagement therewith, spaced legs embracing the lower rack bar and cooperating with the bar to limit the swinging movements of the stop, and a bridge connecting the arms and legs and disposed between the bars and slidably engaging in the upper and lower grooves of the bars, a spring mounted on each stop for cooperation with the upper bar for frictionally retaining the stop against the lower bar in either extreme position of movement of the stop, the distance between the upper edge of the bridge and the top wall of the associated upper groove being considerably greater than the length of the legs whereby said stop can be raised bodily against the tension of the spring and then swung transversely of the frame to a disengaged position with respect to the latter, and a displaceable limiting stop mounted on the upper rack bar for cooperation with a plurality of column stops to normally prevent the latter from becoming accidentally removed, said limiting stop comprising a plate extending longitudinally of the frame and attached to the upper surface of the upper rack bar, the longitudinal edges of the plate cooperating with the upper ends of the arms of the column stop to limit the upward movement of the latter. 30
8. In a column stop unit for typewriting and like machines, the combination of a frame including a pair of rack bars arranged in a fixed and parallel relation and having their inner faces provided with opposed pairs of transverse grooves arranged at spaced intervals, and a plurality of column stops individually mounted for removal in the respective opposed pairs of grooves of the rack bars, each stop comprising spaced arms embracing the upper rack bar and having pivotal engagement therewith, spaced legs embracing the lower rack bar and cooperating with the bar to limit the swinging movements of the stop, and a bridge connecting the arms and legs and disposed between the bars and slidably engaging in the upper and lower grooves of the bars, a spring mounted on each stop for cooperation with the upper bar for frictionally retaining the stop against the lower bar in either extreme position of movement of the stop, the distance between the upper edge of the bridge and the top wall of the associated upper groove being considerably greater than the length of the legs whereby said stop can be raised bodily against the tension of the spring and then swung transversely of the frame to a disengaged position with respect to the latter, and a displaceable limiting stop mounted on the upper rack bar for cooperation with a plurality of column stops to normally prevent the latter from becoming accidentally removed, said limiting stop comprising a plate extending longitudinally of the frame and attached to the upper surface of the upper rack bar, the longitudinal edges of the plate cooperating with the upper ends of the arms of the column stop to limit the upward movement of the latter. 35
9. In a column stop unit for typewriting and like machines, the combination of a frame including a pair of rack bars arranged in spaced parallel relation and with the transverse grooves thereof disposed opposite each other, end plates secured to the ends of the bars, column stops mounted in the grooves of the bars and movable transversely of the bars from an inactive to an active position and vice versa, said bars having transverse seats formed in their outer faces, and a tie plate connecting the bars and having interlocking engagement in said seats. 40
10. In a column stop unit for typewriting and like machines, the combination of a frame including a pair of rack bars arranged in a fixed and parallel relation and having their inner faces provided with opposed pairs of transverse grooves arranged at spaced intervals, a plurality of column stops individually mounted for removal in the respective opposed pairs of grooves of the rack bars, each stop comprising spaced arms embracing the upper rack bar and having pivotal engagement therewith, spaced legs embracing the lower rack bar and cooperating with the bar to limit the swinging movements of the stop, and a bridge connecting the arms and legs and disposed between the bars and slidably engaging in the upper and lower grooves of the bars, a spring mounted on each stop for cooperation with the upper bar for frictionally retaining the stop against the lower bar in either extreme position of movement of the stop, the distance between the upper edge of the bridge and the top wall of the associated upper groove being considerably greater than the length of the legs whereby said stop can be raised bodily against the tension of the spring and then swung transversely of the frame to a disengaged position with respect to the latter, and a displaceable limiting stop mounted on the upper rack bar for cooperation with a plurality of column stops to normally prevent the latter from becoming accidentally removed, said limiting stop comprising a plate extending longitudinally of the frame and attached to the upper surface of the upper rack bar, the longitudinal edges of the plate cooperating with the upper ends of the arms of the column stop to limit the upward movement of the latter. 45
11. In a column stop unit for typewriting and like machines, the combination of a frame including a pair of rack bars arranged in spaced parallel relation and with the transverse grooves thereof disposed opposite each other, end plates secured to the ends of the bars, column stops mounted in the grooves of the bars and movable transversely of the bars from an inactive to an active position and vice versa, said bars having transverse seats formed in their outer faces, and a tie plate connecting the bars and having interlocking engagement in said seats. 50
